Ornamental design for a dustpan comprising a device allowing a removable handle to be fitted thereto, as shown and described.

DESCRIPTION

The patent or application file contains at least one drawing executed in color. Copies of this patent or patent application publication with color drawing(s) will be provided by the Office upon request and payment of the necessary fee.

1. Dustpan comprising a device allowing a removable handle to be fitted thereto

1.1 is a perspective

1.2 is a perspective of the dust pan.

1.3 is an enlarged perspective view of the dustpan and handle.

1.4 is an enlarged perspective view of the dustpan and handle.

1.5 is a greatly enlarged view of a portion of the dustpan.

1.6 is a perspective view of the handle.

Dustpan with handle having a system that allows a second vertical handle to be attached with a simple clip; left-hand and right-hand flanges allowing the dustpan to be held in place with the feet, leaving both hands free; without bending down, the dustpan is secured on the ground, but extends up to the desired height; view 1: handle with "Pelgé" system and, at the other end, a standard screw thread that can be fitted to any brush; view 3: attachment position; view 4: lease; view 5: flanges with logo, two grooves to the rear of the dustpan lock the system using a simple movement towards the ground, with a slight forward movement being used to release same.
